UNITED STATES PATENT OFFICE.

WILLIAM H. WINSLOW, OF CHICAGO, ILLINOIS, ASSIGNOR TO THE STEAM POWER DEVICES COMPANY, OF CHICAGO, ILLINOIS, A CORPORATION OF ILLINOIS.

SYSTEM OF WATER-LEVEL INDICATION FOR BOILERS.

1,279,485.

Specification of Letters Patent. Patented Sept. 17, 1918.

Application filed March 8, 1912. Serial No. 682,528.

To all whom it may concern:

Be it known that I, WILLIAM H. WINSLOW, a citizen of the United States, residing at Chicago, in the county of Cook and State of Illinois, have invented a certain new and useful Improvement in Systems of Water-Level Indication for Boilers, of which the following is a full, clear, concise, and exact description, reference being had to the accompanying drawings, forming a part of this specification.

My invention relates to an improved system of water level indication for boilers by which a comparatively small difference in the level of the water in the boiler produces a relatively large change in the indication of the indicating mechanism, and furthermore by my invention the indicating mechanism may be placed at a point remote from the boiler itself and the changes in level in the boiler accurately indicated by said indicating mechanism.

My invention further consists in novel devices for use with a steam boiler so that the level of the water therein may be more effectively indicated than by means of the ordinary water gage heretofore used in the art. My system of water level indication and the devices specially adapted for use therewith may be employed in connection with water level boilers generally and particularly with any type of boiler in which the changes in level are required to be great and in which the amount of water contained in the boiler is relatively small and where the heating zone extends above the water level, such for example, as automobile boilers.

The several drawings illustrating my invention are as follows:

Figure 1 shows diagrammatically in plan view a boiler provided with devices for indicating the level of the water in the boiler in accordance with my system.

Fig. 2 shows diagrammatically in side view the parts indicated in Fig. 1, and in this figure in addition there is shown a means for supplying water to the boiler.

Fig. 3 shows in detail elevation a gage for indicating the level of the water.

Similar numerals refer to similar parts throughout the several views.

As shown in Figs. 1 and 2, the boiler consists of a plurality of sets of tubes 1, 2, 3, 4, 5, 6, each set extending between vertical end

headers as shown for the tubes 6 at 7 and 8, the tubes between the headers being substantially horizontal at the top and inclined at the bottom as indicated. The right hand vertical headers are connected as shown with a steam header 9 at the top and a water header 10 at the bottom and from the steam header connection is made by a pipe 11 through a throttle valve 12, through a pipe 13 connecting with the superheating coil 14 extending over the fire beneath the boiler tubes. The superheater 14 is connected by a pipe 15 with a metal chamber 16 in the right hand end of which there is securely threaded a heat responsive element 17 connected with a flexible conducting medium 18 to a gage 19 mounted in convenient position for observation, which, in the drawings, is assumed to be upon the dash-board of an automobile, the boiler being of a type adapted for use in connection with such a machine. The detail construction of the heat responsive element 17 and its connecting mechanism 18 to the gage 19, is not shown in detail, as devices of this kind are known in the art, and since the gage 19 is constructed in a manner well known in the art so that changes of pressure exerted upon it will move a pointer 21, shown in Fig. 3, proportionately to said pressure, which, for the construction indicated, is communicated to the gage through a small bore tube constituting, for the construction shown, the conducting medium 18, such tube being in communication with a body of fluid contained in the heat responsive member 17, such fluid having a high coefficient of expansion, as, for example, mercury. As a result, when the body 17 is subjected to an increase in the temperature, the fluid expands and pressure is communicated through the small tube to the gage 19 and the pointer 21 is rotated to indicate the increased temperature in the chamber 16. The chamber 16 has extending from its lower surface, a tube 22 supported by a bracket 23 from a bar 24, forming a part of the structure of the vehicle, and this tube is connected by a coupling 25 with a pipe 26 leading to the engine to be driven by the boiler.

The water header 10 is connected by pipe 27 through a two-way valve 28 with a supply pipe 29 extending through a check valve 30 to a water pump 31 operated by means of a piston 32. The valve 28 is also

connected by a by-pass pipe 33 with the water supply pipe 34 connected through a check valve 35 with the pump 31. When the valve lever 36 is in the position indicated in the full lines, the operation of the pump 31 forces water through the pipe 29, the valve 28, and the pipe 27 into the water header 10, to thus raise the level of the water in the boiler, and when the valve 36 is moved to the position indicated in dotted lines, communication between the pipe 29 and the pipe 27 is interrupted and the pipe 33 is placed in communication with pipe 29, thus permitting the water delivered from the pump 31 to by-pass into the supply pipe 34.

As previously explained, the water level need not remain at any fixed height, and in fact during generation of steam there is no determinable water level. This is not detrimental but is in fact beneficial in generating steam as it permits of the peculiar steam generating action which is proper to this type of boiler, permitting the boiler to be worked with a variable water content. The entire boiler both above and below the surface of the water is exposed to the furnace heat. This permits of a transfer of heat to the steam in proportion to the amount of steam heating surface that is exposed. This transfer of heat to the steam effects drying and superheating to a greater or less degree, hence a variation of water content does not affect the character of the operation carried on in the boiler, but affects only the degree. If the water content is high there is less steam heating surface and the steam will have less superheat, or will be more wet, as the case may be, and if the water content is low there is more steam heating surface and the steam will be more dry, or will have more superheat for the same gage pressure.

When the boiler provided with the indicating device above described is operated, steam is delivered from the various sets of tubes to the steam header 9 and thus through the throttle 12, to the superheating coil 14 and through the chamber 16 to the engine. When the level of the water in the boiler is raised there is a greater tendency of the water to prime, and this results in a small amount of water being carried over with the steam to the superheating coil 14, as a result of which the steam is not heated as hot as for a somewhat lower level of the water in the boiler. This decrease in temperature is communicated through the devices 17 and 18 to the gage 19 which responds by motion of the pointer 21 around to the left to show that the water in the boiler is higher than normal. As the level of the water increases the amount of water carried over with the steam increases due to the decrease of steam heating surface,

and the pointer 21 is moved still farther around to the left owing to the capacity of the superheater being to a degree overcome by the water in the steam. As a result of the indication afforded, the valve lever 36 is moved to a position to interrupt communication between the pipes 27 and 29 and to by-pass the water pumped, through the pipe 33, for which condition the water level in the boiler drops and the pointer 21 moves around to the right to a corresponding degree. When the water level in the boiler drops below its normal position, the tendency for the water to prime is much decreased due to the increased steam heating surface and very little water is carried over from the steam header 9 into the pipe 13, as a result of which the steam delivered from the superheating coil 14 is much hotter than before, and this condition is communicated by the devices 17 and 18 to the gage 19, and when the water becomes very low, the pointer 21 moves around to the right to its position indicating the low water mark. For this condition, the valve lever 36 is moved to the position shown in Fig. 2 to again establish communication between the pump 31 and the water header 10, cutting off communication with the by-pass 33.

I have not described the boiler construction shown herein in detail as it forms the basis of a number of copending applications including the following: Serial No. 841,445, filed May 28th, 1914, Serial No. 859,157, filed August 29th, 1914, and Serial No. 656,179, filed October 23rd, 1911. With this type of boiler it is to be borne in mind that the circulation of the water is very rapid and that the expression "water level" is only a relative one particularly when the boiler is used in connection with automobile work, since the agitation of the water and its strong circulating action changes the upper surface from level condition to an irregular and inclined condition which is somewhat higher in the headers 7 from what it is in the headers 8 and therefore the gage 19 may be regarded as an indicator of the quantity of water in the boiler whether the upper surface of the water is level or not. However, for conditions which permit the establishment of strict water level, the gage 19 is equally effective for indicating the level for the same reasons pointed out above.

The rapid circulation of the water in the boiler constructed as indicated above is a direct result of the tubes being relatively small and numerous and as the quantity of water contained in the boiler is decreased the agitation and circulation of the water becomes more marked, until for an amount of water which is barely sufficient to fill the lower tubes, the circulating action is so violent as to produce a species of water hammer giving out from the boiler a creak-

ing or scraping sound which is an audible indication to the operator of the low condition of the water if for any reason he should not give heed to the visible indication given 5 by the gage 19. As pointed out in my copending applications above referred to, the separate boiler units consisting of the tubes connected at their ends with headers 7 and 8, are in effect single, homogeneous structures, since they are secured together by fusion by means of the oxy-acetylene flame, and therefore the quantity of water in the boiler may be very small without any damage at all, and in fact the water may be en- 10 15 20 25 30 35 40 45 50

tirely evaporated and the tubes overheated without in any way interfering with the normal operation of the boiler as soon as the other coöperating parts are in condition to again supply water to the boiler. As further pointed out in my copending application referred to, each boiler unit comprises two circulatory systems, one of which contains the water to be heated and transformed into steam and causes its rapid circulation through the tubes in order to bring it effectively into contact with the portions of the tubes heated by the fire. The other circulatory system, which intimately coöperates with the water-heating system, serves to receive the steam from the water-heating system and separate from it the entrained water, which water is either returned to the water-circulatory system, or, if it be of but small quantity, is turned into steam by the heat communicated to the tubes of the steam-separating system. These two circulatory systems, as pointed out, are of varying extent, the dividing line between the two being determined by the quantity of water in the boiler. It is to be understood that the tubes both above and below the water level are heated to a comparatively high temperature. It is obvious, of course, that the pump 31 must have a capacity slightly greater than the maximum load that is to be placed at any time upon the boiler and that the superheating coil 14 shall have a capacity for superheating the steam somewhat for the normal amount of water in the boiler and a greater amount for a low condition of the water in the boiler.

While I have shown my invention in the particular embodiment herein described, I do not, however, limit myself to this particular arrangement or construction of parts, since equivalent boiler constructions may be employed and other arrangements of mechanism may be used which will secure equivalent results.

60 What I claim is:

1. The method of indicating water level in a boiler from which the steam flows which method consists in generating steam, more or less wet according to the level of water in the boiler, heating the steam, and causing

the flowing steam thus heated to act upon a thermally responsive indicator to indicate the level of water in the boiler.

2. In combination a water tube boiler the tubes of which are adapted to be heated above the water level, said boiler being provided with a superheater, a steam delivery pipe, a heat responsive device in contact with the steam delivered from the superheater, and a gage graduated in terms of water level, said gage connected with said heat responsive device and showing by its indication the level of the water in the boiler.

3. In combination a boiler having a variable steam space, means to heat said variable steam space to a temperature higher than the temperature of the water in the boiler, a delivery pipe for steam, a heat responsive device in contact with the delivered steam and a gage or indicator connected to said heat responsive device, said gage or indicator being graduated in terms of water level.

4. In a system of water indication for boilers, the combination of a boiler having a variable water level and having a heating surface extending above said water level, a superheating coil, a delivery pipe connected thereto, a throttle valve between the boiler and the superheating coil, a chamber connected with the delivery pipe of the superheating coil, a steam pipe extending from the chamber, a heat responsive element in said chamber, and a gage for indicating the quantity of water in the boiler, said heat responsive element having a flexible conducting medium between the heat responsive device and the gage.

5. In a system of water indication for boilers, the combination of a boiler having a variable steam space in contact with the fire, a steam delivery pipe from the boiler, including a superheating coil, a metal chamber connected in the pipe beyond the superheating coil, a tube extending from the metal chamber to deliver the steam from the superheating coil, a heat responsive device located in the chamber, a water indicating gage located at a distance from the boiler, and a flexible tube connecting the heat responsive device with the gage.

6. In a system of water indication for boilers, the combination of a boiler having a variable water level and a heating surface extending above said water level, a steam discharge pipe for the boiler including a superheating coil and a chamber beyond the superheating coil, a gage for indicating the water content of the boiler, a thermally sensitive device in said chamber, and connecting means between the sensitive device and the gauge.

7. In a system of water indication for boilers, the combination of a boiler having a

variable water level and a heating surface extending above the water level, a pipe for delivering steam from the boiler to an engine to be driven thereby, a thermally sensitive element subject to the steam in said pipe, a gage for indicating the water content of the boiler, and means connecting the gage with said sensitive element for operating the gage according to the quantity 10 of water in the boiler.

8. In a system of water indication for boilers, the combination of a boiler, having a variable water level and a heating surface extending above the water level, a pipe for delivering steam from the boiler, a gage 15 for indicating the water content of the boiler, a thermally expansive element subject to the steam in said delivery pipe, and means for communicating expansion from the thermally expansive element to the gage proportionately to the temperature changes in the thermally expansive element.

9. In a system of water indication for boilers, the combination of a boiler, having

a variable water level and a heating surface 25 extending above the water level, a steam delivery pipe from the boiler, a gage for indicating the water content of the boiler, a thermally controlled device connecting the gage with the steam delivery pipe for operating the gage to indicate the quantity of water in the boiler by changes in the temperature of the steam delivered therefrom. 30

10. The method of indicating water level in a boiler which consists in generating 35 steam from the water, applying heat to said steam as it moves from the water level to the exit, then measuring the water level by means responsive to the temperature of the steam thus heated. 40

In witness whereof, I hereunto subscribe my name this 29th day of February, A. D. 1912.

WILLIAM H. WINSLOW.
